UNITED STATES PATENT OFFICE

RICHARD ARTEL SLAUGHTER, JR., OF TOPEKA, KANSAS

DESIGN FOR AN AUTOMOBILE

Application filed May 2, 1930. Serial No. 35,477. Term of patent 14 years.

To all whom it may concern:

Be it known that I, RICHARD ARTEL SLAUGHTER, Jr., a citizen of the United States, residing at Topeka, in the county of Shawnee and State of Kansas, have invented a new, original, and ornamental Design for an Automobile, of which the following is a specification, reference being had to the accompanying drawing, forming part thereof.

Figure 1 is a front elevation of my automobile.

Fig. 2 is a side elevation thereof, and

Fig. 3 is a rear elevation thereof.

I claim:

The ornamental design for an automobile as shown.

RICHARD A. SLAUGHTER, JR.
